UNITED STATES PATENT OFFICE

DECIDERIO TRUJILLO, OF DENVER, COLORADO

SWIMMER'S SPEED ACCELERATING DEVICE

Application filed November 5, 1931. Serial No. 573,102.

My invention relates to a swimmer's speed accelerating device. And the objects of my invention are:

First, to provide a device that is adapted to be attached to the feet of swimmers that will enable them to exert an additional pressure against the water to that of their bare feet, on the outward strokes of their feet against the water and that will increase the speed of the swimmer through it.

Second, to provide a swimming speed accelerating device that is attached to the feet of the swimmer and acts to increase the speed of swimming forward on the kicking out stroke of the feet and also acts to move and hold the body upward against sinking as long as a slight swimming movement of the feet is maintained.

Third, to provide a swimming shoe that is adapted to be worn by swimmers and that will enable them to swim faster in a straight line and to turn corners or angles and even into an opposite direction in a fraction of the time they can turn with bare feet and legs.

I attain these objects by the mechanism illustrated and described in the accompanying drawings and specification, in which,

Fig. 1 is a side elevation of the device as it appears when secured to the foot of the swimmer, the wings being closed.

Fig. 2 is a bottom plan view of the same, the wings being shown in open or spread positions.

Fig. 3 is a sectional view on the line 3—3 of Fig. 2.

Fig. 4 is an underside perspective view of the device, the chains and fastening straps being removed.

Fig. 5 is a central longitudinal sectional view thereof.

Referring to the accompanying drawings:

The numeral 1 refers to the base or foot plate of the device, which is in the form of a thin rectangular metal plate, preferably aluminum, and 2 the wings which are pivotally secured to the long sides of the plate 1, by hinges 3. Upon the top side of the foot plate is secured a pad 4 of any suitable material such as rubber, or linoleum, which prevents the foot of the wearer from contact with the

metal foot plate. To the underside of the foot plate, and near the front and rear ends thereof, are riveted transverse channel bar sections 5 and 6 respectively, which are of the same width as the foot plate, but of less depth than the width of the wings 2, and a similar channel section 7, is also riveted to the plate centrally of its width, and extends from the section 6 to the heel end of the plate. The purpose of the sections 5, 6 and 7 will be later explained. The ends of the sections 5 and 6, define the closed or folded positions of the wings, and the open or spread positions of the wings are defined in the following manner:

Two eye bolts 8 are secured to each wing, in line with the channels 5 and 6, the shanks of the bolts passing through nuts 9 on opposite sides of the wing, and the eyes being on the inner sides of the wing and being bent at angles to the shanks so as to lie in substantially horizontal positions when the wings are spread, as clearly shown in Fig. 3. To each eye bolt is secured a chain comprising a pair of swivel links 10 and a snap hook 11, and each two opposing hooks are adapted to engage a ring 12, thus connecting the wings and limiting outward movements. The chains and their connecting ring 12, lie within the channels 5 and 6, respectively, and a bolt 13 passes through each of the channels and through each of the rings 12, thus supporting the rings, but permitting them to have a limited lateral movement in either direction. A substantially Z-shaped plate 14, is riveted to the forward end of the foot plate. This plate extends the full width of the foot plate, and presents an upright portion at right angles to the foot plate, a lower step portion which is secured to the under side of the foot plate, and an upper step portion to which is riveted a clip 15 to which is secured one end of a strap 16, the free end portion of which is provided with a suitable buckle 17 which is adjustably mounted thereon. The plate 14 may be an integral part of the foot plate, if desired. A strap 18 passes through the channel 5 and is secured by a split pin 19 which passes through it and through the foot plate and pad 4 as shown in Fig. 5. This strap is

passed up around the edges of the foot plate and over the forward portion of the foot, and one of its ends is provided with a buckle 20. Another strap 21 is passed through slots 22 in the foot plate and pad 4, and is passed up over the instep, one of its ends being provided with a buckle 23, and this strap carries a heel strap 24, the ends of which are hooked around the said strap 21, which is secured 10 to the foot plate by a split pin 15, in the same manner as the strap 18. The free end of the strap 16 is passed around the strap 21, and when drawn upon and secured by the buckle 17, the heel strap is caused to hug the 15 back of the foot and thus prevent forward slipping movement of the device, while the straps 18 and 21, hold the foot plate to the bottom of the foot and also prevent backward slipping of the same, as will be understood by reference to Fig. 1. Straps of suitable woven material are preferably used, as they are not affected by water, and dry out quickly.

In practice, the swimmer secures one of 25 the devices upon each foot and in the act of swimming, he uses his legs in the manner natural to swimmers. Upon each propelling stroke of the leg, the impact of the wings upon the water causes them to spread to the limit 30 of their movements as defined by the chains, and the wings which are each two inches, in width in addition to the foot plates, which are nearly four inches in width, provide a 35 propelling surface for each foot which is more than double the surface of the sole of the foot, and the increased resistance offered by the impact of this greatly increased propelling surface upon a correspondingly increased water surface, results in greatly increasing 40 the propelling force of the swimmer, and thereby materially increasing his speed through the water. On the reverse movements of the legs, the wings are automatically 45 folded against the ends of the channels 5 and 6, and thus offer no resistance to the water, so that the swimmer exerts no more effort when equipped with the improved accelerating devices than he would when swimming without them.

The plate 14, at the toe end of the foot plate, 50 assists in maintaining the level of the legs while swimming, as they offer sufficient resistance to the water to prevent the feet from being forced downward on the propelling strokes of the legs. When swimming in a straight course, the wings spread evenly as 55 shown in Fig. 3, but in turning, the stroke of the legs is not in a direct line, and the pressure on one wing may be greater than the pressure on the other wing, and this uneven pressure causes a lateral shifting of the chains until stopped by the rings 12, which permit the wings to stand at different angles to the 60 foot plate, as indicated by the dotted lines in

Fig. 3, and thus accommodate themselves to the change in the direction of the stroke.

To enable the user to walk with comfort while wearing the device, it is only necessary to release the hooks 11 from the rings 12, 70 and turn up the wings so that they will stand at right angles to the foot plate, and secure them in these positions by snapping the hooks 11 into a ring 26 which is attached to the strap 16, as shown in Figures 1 and 5. The weight 75 of the person will then be borne by the channel members 5, 6 and 7, which will afford firm hold upon the beach and prevent slipping by contact with stones or shells.

Having described my invention, what I 80 claim as new and desire to secure by Letters Patent, is:—

1. In a speed accelerating device for swimmers, a foot plate and securing means therefor, wings hinged to the long sides of said plate, pairs of chains secured at one end to each wing and having hooks on their free ends, a ring connecting the hooks of each pair of oppositely positioned chains, supports on the foot plate and bolts which pass through said supports and said rings, said chains limiting the spread of said wings.

2. In a speed accelerating device for swimmers, a foot plate and securing means therefor, wings hinged to the long sides of said plate, channel bars secured to the bottom of said plate, adjacent the ends thereof, a bolt passing centrally through the sides of each channel bar, and rings supported on said bolts, chains connected at one end to each wing and having hooks on their free ends, the hooks of each pair of opposite chains being connected to one of said rings thereby to limit the spread of the wings.

3. A speed accelerating device for swimmers, comprising a foot plate having securing straps thereon, wings hinged to opposite sides of said plate, a transverse channel bar on the bottom of said plate near each end thereof, bolts extending through said channel bars and rings supported thereon, chains secured at one end to each wing and having hooks on their free ends, two opposite chains being hooked to one ring thereby to limit the spread of the wings, said wings being turned up at right angles to the foot plate to permit walking and a ring on one of said straps to which opposite chains are hooked to hold the wings in such positions.

In testimony whereof, I affix my signature. 120
DECIDERIO TRUJILLO.
